UNITED STATES PATENT OFFICE.

HENRY B. UNRUH, OF GREAT BEND, KANSAS.

RAILROAD-RAIL.

No. 884,690.

Specification of Letters Patent.

Patented April 14, 1908.

Application filed April 12, 1907. Serial No. 367,725.

To all whom it may concern:

Be it known that I, HENRY B. UNRUH, a citizen of the United States, residing at Great Bend, State of Kansas, have invented 5 certain new and useful Improvements in Railroad-Rails, of which the following is a specification.

My invention relates to railroad rails and more particularly to the shapes of the ends 10 of the rail members whereby the ends of adjacent rail members may be interlocked to form a substantially unbroken continuous rail or track.

The primary object of the invention is to 15 provide a rail member which is particularly simple in construction and highly efficient in use.

Other objects of the invention will be appreciated from the device as hereinafter described.

The invention is illustrated in the accompanying drawings in which

Figure 1 is a perspective view of one rail member. Fig. 2 is a plan view of the rail 25 joint formed with my improved rail members and Fig. 3 is a transverse sectional view of the same.

The invention includes generally a joint in which each rail member is provided with a 30 pocket or recess extending vertically through the head, web and base thereof, a second pocket or recess extending vertically through the web and base, a third recess extending through the base only, and co-acting shoulders or surfaces adapted to interlock with the walls of similar recesses in a companion rail member. As will be understood, the co-acting ends of adjacent rail members are formed complementary to each other.

As herein illustrated, the end of each rail member is formed by a reduced extension 1 of substantially one-half the full width of the rail, which extension has a flat perpendicular side 2 located in the vertical plane of the center of the rail, which side terminates at its rear end in and constitutes one side wall of a substantially V-shape pocket or recess 3, the other wall of which, designated 4, is formed by the beveled end of the part of the rail at 45 one side of the reduced extension. The pocket 3 extends vertically through the head, web and base of the rail member. The front end of the extension 1 is beveled as indicated at 5, the latter surface extending at substantially the same angle or in parallelism with the surface 4. Each extension 1 terminates

in a tongue 6 which is provided with a bevel front edge 7 and an upper surface arranged in the horizontal plane of the bottom of the head of the rail and is further provided with 60 an outer face substantially in the vertical plane of the outer side of the head of the rail and an inner face substantially in the vertical plane of the outer face of the usual web, the latter face, designated 8, forming with 65 the part of the surface 5, below the head of the rail, a substantially V-shape pocket 9. One end of the base flange of the rail member is substantially in transverse alinement with or terminates at the base of the bevel 7 of the 70 tongue 6 and the other flange of the rail member extends from the opposite side of the web a distance to the rear of the recess 3 substantially corresponding to the length of the tongue 6. A substantially V-shape 75 pocket or recess 10 is formed at the juncture of this base flange and the web of the rail member. The webs of the rail members at the ends of the same are preferably thickened so that the outer sides thereof are in 80 substantially the vertical planes of the outer side of the rail heads, as described, and the tongues 6 form continuations of these thickened parts.

The structure defined includes, as will be 85 noted, three recesses or pockets substantially of V-shape, the innermost of these pockets, designated 3, extending vertically through the head, web and base of the rail member, the pocket 9 extending through the web and 90 base of the rail and the pocket 10 extending through the base of the rail member only. The structure also provides three substantially V-shape noses, or projections, adapted to interlock with recesses, corresponding to 95 those described, in the end of the adjacent rail member.

The adjacent ends of two rail members are joined by a relative longitudinal movement of the two with the parts held in proper 100 register.

In the completed joint the nose on the end of the tongue 6 fits within the recess 10, in the companion rail member, the nose on the extension 1 fits within the recess 3 and the 105 nose on the web and base formed in part by the side 4, fits within the pocket 9 while the bevel side 4 of the rail-head co-acts with the similarly bevel surface 5 on the co-acting rail member.

To bind the parts securely suitable transversely extending bolts 11 are provided

which may have associated therewith suitable nut locks. To further hold the parts together, a chair 12 is preferably provided for each joint. This chair consists of a substantially channel plate which extends between and is secured to adjacent ties. The upper flat surface of the plate provides a support for the base of the rail and the flanges at the side of the chair abut against the outer edges of the base of the rail to prevent the rail members spreading transversely.

I claim:

1. A rail member having a recess extending vertically through the head, web and base thereof, a second recess in advance of the first extending through the web and base of the rail member, and a third recess to the rear of the first extending through the base of the rail only.
2. A rail member having a recess extending vertically through the head, web and base thereof, a second recess in advance of the first extending through the web and base of the rail member, a third recess to the rear of the first extending through the base of the rail only, and interlocking projections on the rail member adapted to fit within corresponding recesses in a co-acting rail member.
3. A rail member, having an extension at the end thereof having a flat perpendicular face located substantially in the vertical plane of the center of the rail, and a substantially V-shape nose at its forward end, said rail member having a recess at the rear

end of said extension of the full height of the rail, a tongue extending forwardly from the end of the extension below the head of the rail terminating in a substantially V-shape nose and having a flat side in substantially the vertical plane of the outer side of the rail web and forming with the nose of the extension a substantially V-shape recess, one of the flanges of the rail terminating at the base of said nose of the tongue and the other of the rail flanges extending from the web a distance to the rear of the first named recess and being provided with a recess adjacent the rail web.

4. In a rail joint, two rail members, each having two corresponding bevel surfaces, one located in advance of the other on the rail head co-acting with like surfaces on the other rail member, two corresponding bevel surfaces, one located in advance of the other on the web co-acting with like surfaces on the other rail member, and a reentrant and salient bevel surface on the base co-acting with complementary surfaces on the other rail member, substantially as described.

In testimony whereof, I have hereunto signed my name in the presence of two attesting witnesses at Great Bend, Kansas, this 29 day of March, 1907.

HENRY B. UNRUH.

Witnesses:

JACOB WEDEL,
BENJ. SIEBERT.
